PATENTED JAN. 15, 1907.

W. H. VANDERHERCHEN.

IMPLEMENT FOR DRIVING SCREW HOOKS AND EYES.

APPLICATION FILED FEB. 17, 1906.

UNITED STATES PATENT OFFICE.

WILLIAM H. VANDERHERCHEN, OF PHILADELPHIA, PENNSYLVANIA.

IMPLEMENT FOR DRIVING SCREW HOOKS AND EYES.

No. 841,472.

Specification of Letters Patent.

Patented Jan. 15, 1907.

Application filed February 17, 1906. Serial No. 301,695.

To all whom it may concern:

Be it known that I, WILLIAM H. VANDERHERCHEN, a citizen of the United States, residing in Philadelphia, Pennsylvania, have 5 invented certain Improvements in Implements for Driving Screw Hooks and Eyes, of which the following is a specification.

The object of my invention is to provide a simple and efficient tool whereby a screw-eye 10 or a screw-hook can be firmly held while it is being screwed into position, the tool also providing for the placing of such screw-eyes or screw-hooks in places which would otherwise be inaccessible.

15 In the accompanying drawings, Figure 1 is a perspective view of a driving-tool for screw-hooks or screw-eyes constructed in accordance with my invention. Fig. 2 is a view, partly in side elevation and partly in 20 transverse section, showing the parts in position for the insertion of a screw-eye into the driving-tool. Fig. 3 is a similar view showing the parts in the position assumed by them after the screw-eye had been locked in 25 position in the driving-tool. Fig. 4 is an end view of the tool with the parts in the position shown in Fig. 2. Fig. 5 is a similar view, with the parts in the position shown in Fig. 3; and Figs. 6 and 7 are views similar to Figs. 30 3 and 4, respectively, but illustrating another form of the tool.

In Figs. 1 to 5 of the drawings, 1 represents a stem suitably secured to an operating-handle 2, which may constitute part of a 35 pole or staff when it is desired to place the screw eye or hook in a position otherwise inaccessible.

The stem 1 has a head 3 with a transverse slot 4 in its outer end, and mounted upon said 40 head, so as to be capable of rotation thereon, is an inverted cup-shaped cap 5, which also has a transverse slot in its rounded outer end, the cap being retained longitudinally upon the head 3 by means of pins 7, projecting 45 from said head into segmental slots 8 in the cap, as shown in Fig. 1, these slots 8 also serving to limit the extent of rotative movement of the cap on the head.

In order to apply the screw-eye to the im- 50 plement, the cap 5 is turned to such position that its slot 6 is parallel with the slot 4 of the head, as shown in Figs. 2 and 4, and the eye is passed through the slot 6 and into the slot 4, as shown in Fig. 2. The cap 5 is then 55 turned to the extent of a quarter-turn, so as

to bring its slot 6 at a right angle to the slot 4, as shown in Figs. 3 and 5, the result being that the eye of the screw is longitudinally confined within the slot 4, and by engagement with the walls of said slot is readily 60 turned by means of the handle 2.

After the screw-stem has been driven home the implement is readily released from the eye by turning back the cap 5 until its slot 6 again registers with the slot 4 of the 65 head 3 and then withdrawing the implement longitudinally until it is free from engagement with the eye.

In that form of the tool shown in Figs. 6 and 7 the cap 5 is secured to the head 3, and 70 a rotatable continuation 3^a of said head, disposed within the cap 5, engages the head of the screw hook or eye. In this case no special manipulation is needed in order to lock the screw hook or eye to the tool, as the first 75 partial turn of the handle 2 after the application of the head of said screw hook or eye to the tool effects this result.

An instrument of the character described provides for the use of both hands, one for 80 supporting the instrument and the other for turning the same, whereas when the screw eye or hook is directly manipulated only one hand can be used, and difficulty is frequently experienced in getting a proper bite of the 85 screw upon the wood at the start, especially if the wood is hard. The screw eye or hook, therefore, frequently drops from the hand in attempting to get a fresh hold upon the same, because the partial turn originally 90 imparted to the screw has not been sufficient to insure a proper supporting-hold of the same upon the wood. It will be evident that an implement of the character which I have devised effectually overcomes this ob- 95 jection.

I claim—

1. In an implement for driving screw eyes or hooks, the combination of a handle having a head and a cap, the latter having a slot 100 elongated to permit of the passage of an eye or hook and having its interior surface designed to conform to the shape of such an eye or hook, the portion of the head covered by the cap having an elongated recess shaped 105 to hold a hook or eye from turning, one of the parts of the implement having a slot and the other a pin projecting into said slot and being rotatably mounted relatively to each other to permit of the slot in the cap and the 110

recess of the head being brought into parallelism or placed at an angle to each other, substantially as specified.

2. In an implement for driving screw eyes or hooks, the combination of a head and cap for the end of the same, the cap being slotted for receiving an eye or hook and the head being provided with an elongated, transverse recess for holding the eye or hook from turning, said head having its engaging portion rotatably mounted within the cap, substantially as specified.

3. In an implement for driving screw eyes or hooks, the combination of a two-part head

and a cap, the cap being slotted to receive an eye or hook, and the head having an elongated, transverse recess for holding the eye or hook from turning, one portion of the head being secured to the cap, and its hook and eye engaging portion rotatably mounted within the cap, substantially as specified.

In testimony whereof I have signed my name to this specification in the presence of two subscribing witnesses.

W. H. VANDERHERCHEN.
